US00D752276S

(12) **United States Design Patent**
Thompson et al.

(10) **Patent No.:** **US D752,276 S**
(45) **Date of Patent:** **** Mar. 22, 2016**

(54) **PENDULUM PIECE**

- (71) Applicant: **Luminara Worldwide, LLC**, Eden Prairie, MN (US)
- (72) Inventors: **Jeffrey Thompson**, Huntington Beach, CA (US); **Douglas Patton**, Irvine, CA (US); **James LaBelle**, Orange, CA (US)
- (73) Assignee: **Luminara Worldwide, LLC**, Eden Prairie, MN (US)

(**) Term: **14 Years**

(21) Appl. No.: **29/510,322**

(22) Filed: **Nov. 26, 2014**

(51) LOC (10) Cl. **26-99**

(52) U.S. Cl. **D26/154**

(57) **CLAIM**

The ornamental design for a pendulum piece, as shown and described.

DESCRIPTION

FIG. 1 is an isometric view of one embodiment of a pendulum piece.

FIG. 2 is a top view of the pendulum piece of FIG. 1.

FIG. 3 is a bottom view of the pendulum piece of FIG. 1.

FIG. 4 is a front view of the pendulum piece of FIG. 1.

FIG. 5 is a side view of the pendulum piece of FIG. 1.

FIG. 6 is a rear view of the pendulum piece of FIG. 1.

FIG. 7 is an isometric view of another embodiment of a pendulum piece.

FIG. 8 is a top view of the pendulum piece of FIG. 7.

FIG. 9 is a bottom view of the pendulum piece of FIG. 7.

FIG. 10 is a front view of the pendulum piece of FIG. 7.

FIG. 11 is a side view of the pendulum piece of FIG. 7; and, FIG. 12 is a rear view of the pendulum piece of FIG. 7.
